(57) **CLAIM**

The ornamental design for a bedstead, as shown and described.

DESCRIPTION

FIG. 1 is a perspective view of a bedstead showing my new design;

FIG. 2 is a front elevational view of the bedstead;

FIG. 3 is a rear elevational view of the bedstead;

FIG. 4 is a left side view of the bedstead;

FIG. 5 is a right side view of the bedstead;

FIG. 6 is a top plan view of the bedstead;

FIG. 7 is a bottom plan view of the bedstead; and,

FIG. 8 is a perspective view of the bedstead, shown in an environment of use.

The broken lines in the drawings are for the purpose of illustrating portions of the bedstead that form no part of the claimed design. The additional broken lines shown in FIG. 8 are directed to environment and are for illustrative purposes only and form no part thereof.

1 Claim, 8 Drawing Sheets
